Inventor
Victor Kaplan
By his Attorney, C. J. G.

UNITED STATES PATENT OFFICE.

VICTOR KAPLAN, OF BRUNN, CZECHOSLOVAKIA.

BLADE OF ROTOR WHEELS.

Application filed March 14, 1928. Serial No. 625,086.

To all whom it may concern:

Be it known that I, VICTOR KAPLAN, citizen of Czechoslovakia, residing at Brunn, in the county of Moravia and State of Czechoslovakia, have invented certain new and useful improvements (for which an application has been filed in France, Dec. 12, 1922), in Blades of Rotor Wheels, of which the following is a specification.

10 This invention relates to the rotor wheels of water turbines and pumps, and consists in an improved construction of the blades of such wheels, whereby increased efficiency is obtained.

15 From the theory of turbines it is well-known that runner wheels with axial admission are without efficiency if the blade profile curves are made in the shape of helical lines of uniform pitch. The same is true of 20 runner wheels with radial admission, if the blade profile curves are constructed according to logarithmic spirals. On the other hand, however, blades shaped in accordance with helical surfaces have great hydraulic 25 and practical advantages, so that their applicability would be immediately insured if such blades would warrant a correspondingly high efficiency. The present invention 30 solves the problem of providing blades shaped in accordance with helical surfaces, which operate with good efficiency.

For this purpose, the invention consists in a construction of blade whereby a definite ratio between the discharge velocities and 35 the entrance velocities of the runner wheel is obtained, as is hereinafter explained in connection with the accompanying drawing, in which,

40 Fig. 1 shows the left-hand side of a turbine runner wheel with a blade S in meridional projection. Fig. 2 shows a blade profile $e_1 a_1$ obtained by the section of the cylinder surface ZZ, Fig. 1, with the blade S developed in the plane of the drawing, with 45 two velocity diagrams. For the sake of greater clearness, this figure has been drawn to a larger scale than Fig. 1.

It is well-known that the angles of the 50 runner wheel can be determined with the aid of the multi-dimensional theory from the velocity diagrams. If therefore in Fig. 1 represents the stream lines of the turbine in the meridional projection, there are thereby determined also the factors of the 55 flow, that is, the pressure and the velocity.

Since, according to the invention at least

a part of the blade profiles shall be made as helical lines, this, for the purpose of obtaining a good efficiency, is possible only if the eddy produced by the distributor is caught by the inlet edge of the blade without considerable losses of impact and is braked as completely as possible by the blade, so that the working fluid leaves the outlet edge without a considerable component of rotation. If therefore one looks at the cylinder section ZZ (Fig. 1), the condition of the flow at e_1 , as well as at a_1 , is perfectly known. Consequently, the inlet and outlet diagram (Fig. 2) can be laid out. However, since only the flow along the cylinder surface ZZ is taken into consideration, one must also calculate those velocities existing in this surface. Therefore, of the meridional inlet and outlet velocities cm_1 and cm_2 , respectively, only their axial component (cm_1) and (cm_2) must be made the basis for the velocity diagrams Fig. 2.

From the premises it follows that the peripheral velocity u_1 existing at e_1 , must be equal to that at the point a_1 , at which it is indicated in the outlet diagram Fig. 2 by u_2 . However, the braking of the eddy induced by the distributor necessary to obtain a good efficiency requires that the component of rotation eu_1 (Fig. 2) existing at the point e_1 , should disappear at the point a_1 . This, however, is possible only if (cm_2) is not only of axial direction, but also possesses a very definite magnitude which can be deduced from the inlet diagram (Fig. 2). For if the blade profile $e_1 a_1$ conforms to a helical line of uniform pitch, when developed it will appear as a straight line. But then the inlet angle β of the runner wheel will become equal to the outlet angle δ of the runner wheel and consequently the axial component (cm_2) of the meridional outlet velocity cm_2 must be made to conform to this fact. As appears from the inlet diagram, this requirement is complied with if (cm_2) can be made equal to (cm_1) by the extension of the latter to the point A where it intersects the extension of the relative inlet velocity w_1 . Then, however, from the similarity of the inlet and outlet triangles, it may be concluded that the requirement

$$\left(\frac{cm_1}{cm_2} \right) = \frac{w_1}{w_2}$$

must be fulfilled, which can be expressed in words in this way, that one can count on a

satisfactory efficiency with blades having helical surfaces, only when the ratio between the axial component of the meridional inlet velocity to that the outlet velocity

$$\left(\frac{cm_1}{cm_2} \right)$$

is equal to the proportion of the relative inlet velocity to the relative outlet velocity

$$\left(\frac{w_1}{w_2} \right)$$

It requires no further argument to show that the stated ratio must at least approximately be reached in regard to all those cylinder sections for which helical profiles of at least approximately uniform pitch are desired. Therefore, either the entire blade, or else only a part thereof, may be shaped as a helical surface. Likewise, consideration of the conditions will show that the diagrams illustrated in Fig 2 contain only the course of flow in cylindrical surfaces and therefore do not indicate the velocities existing in the stream lines.

Such blades compared with the curved blades heretofore used have the advantage of easier manufacture. Likewise, the surface of such blades can be worked and finished with a precision not attainable in the blades heretofore used, which also results in hydraulic advantages.

In the construction of turbine pumps such wheels can be used with particular advantage for the reason that the otherwise inevitable retardation of the relative velocity of flow of the water towards the outlet of the runner wheel in axial wheels does not occur because of the approximately parallel position of the individual blades.

A still further simplification in the manufacture of blades can be obtained if the blades having helical surfaces are replaced by blades having plain or practically plain surfaces. Of course, such a substitution can be made successfully only then, if the requirement stated for helical surfaces

$$\left(\frac{cm_1}{cm_2} \right) = \left(\frac{w_1}{w_2} \right)$$

is at least approximately complied with. This is nearly always true of highly efficient high-speed turbines, so that such blade shapes are particularly suited to high-speed turbines. Toward the hub of the runner wheel, however, also in such high speed turbines one must consider not unfrequently a departure from the plain blade shape, but this does not result in any manufacturing difficulties because on account of mechanical

strength already, one must figure on a corresponding enlargement of the blade near the hub of the runner wheel.

Such blades made in accordance with the invention may either be rigidly connected with the hub of the runner wheel or adjustably arranged. If adjustability of the blades according to my application Ser. No. 854149 is provided for, these blades compared with the heretofore used constructions offer the advantage, that the hydraulic conditions of angle reduction at a reduced admission can be better satisfied. A practically harmful decrease in efficiency does not occur even where the admission is greatly reduced. For giving the rotary blades a good bearing, the use of wing-like blades is recommended such as are described in my application Ser. No. 865208.

If a runner wheel constructed in accordance with the invention shall be used as a turbine runner wheel, it is self-understood that the admission on such a runner wheel must be effected with a correspondingly shaped distributor, and if necessary, by the use of suitable suction pipes, provision must be made for a corresponding recovery in the suction-pipe. Likewise, the entire runner wheel must be filled with flowing water during the operation, hence, the flow must be adjusted according to flow-surfaces. The same measures must also then be taken, if the wheel shall advantageously work in connection with a turbine pump. Therefore, the brief statement suffices, that according to the required reversal of the direction of flow the outlet velocities of the pumps must correspond to the inlet velocities of the turbines, and vice versa.

Patent claims:

1. Runner wheel for turbines and the like, comprising a hub and blades carried thereby, said blades comprising, in part, surfaces so shaped that the proportion, between the axial component of the mean inlet velocity and the axial component of the mean outlet velocity, is approximately equal to the proportion, between the relative inlet velocity and the relative outlet velocity.

2. Runner wheel for turbines and the like, comprising a hub and blades carried thereby, said blades comprising, in part, helical surfaces such that the proportion, between the axial component of the mean inlet velocity and the axial component of the mean outlet velocity, is approximately equal to the proportion, between the relative inlet velocity and the relative outlet velocity.

In testimony whereof I affix my signature.

VICTOR KAPLAN.
